UNITED STATES PATENT OFFICE.

LEON E. HIRT, OF CHARLESTON, WEST VIRGINIA.

METHOD AND APPARATUS FOR FRACTIONATING HYDROCARBONS.

1,222,402.

Specification of Letters Patent.

Patented Apr. 10, 1917.

Application filed July 21, 1915. Serial No. 41,109.

To all whom it may concern:

Be it known that I, LEON F. HIRT, a citizen of the United States, residing at Charleston, in the county of Kanawha and State of West Virginia, have invented a new and useful Method and Apparatus for Fractionating Hydrocarbons, of which the following is a full, clear, and exact description, reference being had to the accompanying drawings, forming part of this specification, in which—

Figure 1 is a view partly in vertical section, and partly in side elevation, and largely conventional in character, showing the preferred form of apparatus for carrying out my invention, and

Fig. 2 is a section on the irregular line II—II of Fig. 1.

My invention has relation to the fractionation or cracking of hydrocarbons; and it consists in the provision of a method and apparatus whereby the fractionation may be carried out in a simple and highly effective manner.

Referring to the accompanying drawings, in which I have shown the preferred form of apparatus for carrying out my invention, the numeral 2 designates a refractory furnace or retort having an upper interior atomizing chamber 3, a central contracted portion 4, and a lower offtake chamber 5. The furnace or retort is heated by means of electric arcs produced between the electrodes 6 which project into opposite sides of the contracted portion 4. 7 designates an oil tank having a connection 8 at one side with the bottom chamber of the retort, and a connection 9 at the opposite side leading to a pump 10. The pipe 9 may have a fresh oil supply connection 11. 12 is a pipe leading from the pump 10 into an atomizing nozzle 13 which projects into a top opening 14 in the retort. 15 is a steam pipe which discharges downwardly within the nozzle 13. The various connections are provided with suitable valves, as indicated.

The pipe 15 preferably supplies superheated or dry steam; and its action is to cause the oil to be discharged into the chamber 3 in the form of a spray or mist which is caused to pass through the arc between the electrodes.

The fractionation or refractionation takes place under a controllable pressure within the retort, which pressure will vary to suit the characteristics of the particular grade of oil being used. The pump 10 maintains the

oil pressure to the desired intensity; and as the spray or mist of oil and steam passes the arc and is partly broken up and fractionated by the intense heat of the arc a pressure is built up within the retort. This pressure is held back and is controlled by means of the valve 16 in the offtake pipe 17. This pipe leads to any suitable condenser or rectifier. Any oil which passes the arcs untreated is trapped off into the tank 7 from whence it may be pumped back for re-treatment, or otherwise disposed of.

The steam introduced with the oil is decomposed into $2H_2 + O_2$, the nascent H_2 entering into the reaction with the oils; and by holding the desired pressure in the furnace chamber, any thermo-chemical compound of the oils can be formed. The O_2 liberated combines with carbon to form CO gas. This is preferable to carbon in the free state, since the latter clogs the furnace and discolors the condensed fractions. Instead of using steam, of course, hydrogen may be supplied either in the form of free hydrogen or by some other gas containing the same, such as natural gas. If in any particular case the O_2 produced by the dissociation is objectionable in causing carbonization or burning, the atomization may be produced by oil pressure alone. I prefer, however, in all cases to have hydrogen present in some form.

The pressure within the retort is a result of the expansion of the gases and can be maintained at a proper degree, any excess being relieved by the valve 16 as the process proceeds.

The furnace or retort is preferably cylindrical in shape, and can be built to stand any desired working pressure. While I have shown only two electrodes, any desired number of these can be employed so as to produce arcs arranged in multiple pairs, causing arc-ing flame to take any desired contour or shape.

By my invention the operation can be so controlled that any desired hydrocarbon of a particular series capable of being produced by fractionation can be readily manufactured. Suitable catalytic agents of known character can be employed in the retort or furnace to assist in any particular reaction that it may be desired to produce. While I have shown the retort or furnace in vertical position, it is obvious that it can be supported in any other desired position.

In referring to pressures herein and in the

appended claims, the term "pressure" is to be understood in its absolute sense, since either positive or negative pressures may be employed.

5 I claim:

1. The herein described method of fractionating hydrocarbon oils, which consists in subjecting an oil in the form of a spray or mist to the action of an electric arc within a closed chamber or retort, maintaining a controllable pressure in said chamber or retort and conducting off and condensing the oil vapors thus produced in said chamber or retort, substantially as described.
- 10 2. The herein described method of fractionating hydrocarbon oils, which consists in subjecting an oil to the action of an electric arc within a closed chamber or retort, maintaining a controllable pressure in said chamber or retort, and conducting off and condensing the oil vapors thus produced in said chamber or retort, substantially as described.
- 15 3. The herein described method of fractionating oils, which consists in subjecting an oil in the presence of hydrogen to the action of an electric arc in a closed chamber or retort, to thereby fractionate the oil and produce a reaction between the hydrogen and the oils, and conducting away the oil vapors thereby produced and condensing the same into a liquid; substantially as described.
- 20 4. The herein described method of fractionating oils, which consists in subjecting oil mixed with steam to the action of an electric arc in a closed chamber or retort, whereby the steam is decomposed and the liberated H_2 enters into reaction with the oils to form a compound thereof, and maintaining a controlled pressure in the retort or chamber to thereby control the character of said compound; substantially as described.
- 25 5. The herein described method of fractionating oils, which consists in subjecting an oil in the presence of hydrogen to the action of an electric arc in a closed chamber or retort, to thereby fractionate the oil and cause a reaction between the oil and the hydrogen, controlling the pressure in the retort or chamber during the operation, and
- 30 6. The herein described method of fractionating oils, which consists in subjecting an oil in the presence of steam to the action of an electric arc in a closed chamber or retort, thereby effecting the decomposition of the steam and causing the liberated hydrogen to enter into reaction with the oils, and
- 35 7. The herein described method of fractionating oils, which consists in subjecting an oil in the presence of hydrogen to the action of an electric arc in a closed chamber or retort, to thereby fractionate the oil and produce a reaction between the hydrogen and the oils, and conducting away the oil vapors thereby produced and condensing the same substantially as described.
- 40 8. The herein described method of fractionating oils, which consists in subjecting an oil in the presence of steam to the action of an electric arc in a closed chamber or retort, thereby effecting the decomposition of the steam and causing the liberated hydrogen to enter into reaction with the oils, and
- 45 9. The herein described method of fractionating oils, which consists in subjecting an oil in the presence of hydrogen to the action of an electric arc in a closed chamber or retort, to thereby fractionate the oil and cause a reaction between the oil and the hydrogen, controlling the pressure in the retort or chamber during the operation, and
- 50 10. The herein described method of fractionating oils, which consists in subjecting an oil in the presence of steam to the action of an electric arc in a closed chamber or retort, thereby effecting the decomposition of the steam and causing the liberated hydrogen to enter into reaction with the oils, and
- 55 11. The herein described method of fractionating oils, which consists in subjecting an oil in the presence of hydrogen to the action of an electric arc in a closed chamber or retort, to thereby fractionate the oil and produce a reaction between the hydrogen and the oils, and conducting away the oil vapors thereby produced and condensing the same substantially as described.
- 60 12. The herein described method of fractionating oils, which consists in subjecting an oil in the presence of steam to the action of an electric arc in a closed chamber or retort, thereby effecting the decomposition of the steam and causing the liberated oxygen to combine with carbon to form CO gas, controlling the pressure in the chamber or retort during the operation,

and conducting away and condensing the oil vapors produced; substantially as described.

65

7. The herein described method of fractionating oils, which consists in subjecting an oil in the presence of steam to the action of an electric arc in a closed chamber or retort, thereby effecting the decomposition of the steam and causing the liberated hydrogen to enter into reaction with the oils, and the liberated oxygen to combine with carbon to form CO gas, controlling the pressure in the chamber or retort during the operation, conducting away and condensing the oil vapors produced, and collecting and re-treating any oil which is not fractionated by the action of the electric arc; substantially as described.

75

8. Apparatus for fractionating oils, comprising a cylindrical furnace having relatively enlarged end chambers and an intermediate connecting portion of relatively smaller diameter, means for producing an electric arc in the last named portion, means for introducing oil and steam in the form of a spray or mist into one of the end chambers, a controllable offtake leading from the other of said chambers, and means for delivering untreated oil from the last named chamber, substantially as described.

80

9. Apparatus for fractionating oils, comprising a closed furnace or retort, a spray nozzle arranged to discharge into one end portion of the chamber of the furnace or retort, means for supplying hydrocarbon to said nozzle, means for producing an electric arc within said chamber, an offtake for the produced oil vapors communicating with the chamber at the opposite side of the electric arc producing means, means for regulating the pressure produced by the vapors generated in said furnace or retort, and means for collecting and taking off untreated oil; substantially as described.

85

10. Apparatus for fractionating oils, comprising a cylindrical furnace having relatively enlarged end chambers and an intermediate connecting portion of relatively smaller diameter, means for producing an electric arc in the last named portion, means for introducing a hydrocarbon into one of said end chambers, an offtake for the produced oil vapors leading from the other of said chambers, and means for controlling the pressure within the retort; substantially as described.

90

11. In testimony whereof, I have hereunto set my hand.

LEON E. HIRT.
